HAND STAMP

Matt M. Corey, Chicago, Ill.

Application March 5, 1935, Serial No. 9,465

7 Claims. (Cl. 101—111)

My invention relates to hand stamps of the dater type, and has for its object improvements in such devices.

In the accompanying drawing:

5 Fig. 1 is a central longitudinal section, at about full size and partly in elevation, of a hand stamp made in accordance with my invention;

Fig. 2 is a transverse section, partly in elevation, on line 2—2 of Fig. 1;

10 Fig. 3 is a section on line 3—3 of Fig. 1;

Fig. 4 is a section of the stamp frame and die holder with the dater element in the process of being inserted or withdrawn;

15 Fig. 5 is a perspective view of the yoke which embraces and holds the dater element; and

Fig. 6 is a plan of the stamp frame.

20 To the die-holding plate 10 is secured a stamp frame consisting of legs 11 and connecting bridge 12, formed from a single piece of metal. The distance between the legs 11 is just sufficient to receive the dater element having legs 13 and shaft 14. The dater element is the same as that in common use except that the bend in the legs at 15 is a little sharper and more pronounced than usual.

25 The yoke for receiving and holding the dater element consists of legs 16 connected by a bridge 17, and is made of spring metal. In the legs 16 are rectangular openings 18 of a size just sufficient 30 to receive those parts of legs 13 which are above the bends 15. The parts 19 of the yoke come just below the bends 15 and serve to hold the dater element firmly within the yoke.

35 The dater element is inserted or removed from the yoke by manually bending the spring legs 16 outward.

40 Riveted to the center of the bridge 17 is a screw 20, and in the bridge 12 is a recess 21 arranged to receive the screw 20 when the dater element is in proper position in the frame. The die-holding element 10 has the ordinary central opening thru which the dater element projects to match a die held in the plate.

45 On the screw 20 are nuts 22 and 23 arranged to engage the upper and lower faces of bridge 12 when said screw is in the recess 21. It will be evident that by turning the nuts 22 and 23, the dater element may be adjusted vertically to make the characters on the bands of the dater come even 50 with whatever characters may be on a die 20 held in the plate 10. When properly adjusted the two nuts serve as a means for locking the dater in position.

A cap 24 fits over the upper part of the stamp frame and encloses the nuts 22 and 23. A handle

25 is screwed on the upper end of the screw 20 and serves to hold the cap in position.

The central part of the cap 24, thru which the screw 20 passes, is stamped to form a recess on the inside to receive the nut 23, and this forms 5 a projecting bearing surface 27 on the upper side against which the handle 25 is screwed. The recess below is of less depth than the thickness of the nut 23 with the result that when the handle is screwed down, it clamps the cap 24 on said 10 nut and thus furnishes a secondary lock for securing the dater element from displacement in the frame.

The manner of inserting the dater element in the yoke has already been described. The manner of inserting the yoke and dater element in the stamp frame is illustrated in Fig. 4, and will be understood without special description. The assembled condition is shown in Figs. 1 and 2.

It is to be noticed that the yoke has the screw 20 secured thereto, and that the dater element is held within the yoke by the spring action of the metal from which the yoke is formed. As thus made, the yoke, dater and screw taken together constitute a self-contained dater unit which may 25 be inserted in or withdrawn from the stamp frame, and this is true whether the nuts 22 and 23 are on the screw or not. In the same way we may say that the frame and die holder are 30 a unit because they are permanently secured together.

Heretofore it has been the practice to raise and lower the dater element with respect to the die element by means of screws and springs properly housed and located over the die holder and at each end of the dater element. Such constructions are relatively expensive to make, are cumbersome in appearance, are not easily adjustable because the adjustments are at two places and must agree, are liable to displacement, and are places for catching dirt.

In the present case, the screw used for holding the handle of the stamp is utilized for all adjustments, and the adjustments are at one place instead of being at two places. When an 45 adjustment is made it is locked in position by the nuts making the adjustment, and the adjusting devices are completely enclosed by a cap held in place by the handle. There are no screws at any place other than the one for the handle, 50 which screw is here used for a double purpose.

What I claim is:

1. In a hand stamp, a yoke of spring metal having openings in its legs, a dater element within the yoke and having the upper portions of its 55

legs fitting into the openings in the legs of the yoke, a die holder, a stamp frame secured to the holder and enclosing the yoke, and means associated with the upper part of the stamp frame for adjusting the elevation of the dater element with respect to a die held in the die holder.

5 2. A hand stamp providing a main frame, a die plate and a die having a dater element therein, a spring yoke within which the dater element is inserted and by which it is held by spring action, and means by which the yoke and the dater element therein are vertically adjusted with respect to the said other parts of the stamp.

10 3. In a hand stamp, a unit consisting of a frame and a die holder rigidly secured together, and a dater unit with adjusting means, said dater unit with its adjusting means being freely 20 inserted in and withdrawn from the frame unit.

4. In a hand stamp, a frame and a die holder, a dater element within the frame, means for adjusting the dater element vertically in the frame, and a cap enclosing the adjusting means.

25 5. In a hand stamp, a die holder with a central opening for the insertion of dating devices,

a frame secured to the holder and having a recess in one side over the center of the opening in the holder, a dater unit having a screw carried thereby and projecting upward from its center, and nuts on said screw, said dater unit with 5 screw and nuts being insertable between the sides of the frame with its lower part projecting thru the opening in the holder and the screw in the recess and said nuts engaging the frame adjacent to the recess to adjust the dater unit in the 10 frame.

6. In a hand stamp, a frame and a die holder, a dater element, means for adjusting the dater element in the frame, a handle for the stamp, and means by which the handle serves as a 15 lock for the adjusting means.

7. In a hand stamp, a unit consisting of a frame and a die holder rigidly secured together, and a dater element having a screw and adjusting nuts, the die holder having a central 20 opening and the frame having a lateral recess over said opening whereby the dater element may be inserted in the frame by lateral and vertical movements with respect to said opening and said recess.

25 MATT M. COREY.
